UNITED STATES PATENT OFFICE.

JOSEPH P. McHUGH, OF NEW YORK, N. Y.

DESIGN FOR A HOLDER FOR UMBRELLAS, CANES, OR THE LIKE.

SPECIFICATION forming part of Design No. 31,205, dated July 11, 1899.

Application filed March 31, 1899. Serial No. 711,286. Term of patent 14 years.

To all whom it may concern:

Be it known that I, JOSEPH P. McHUGH, a citizen of the United States, and a resident of the city, county, and State of New York, have invented and produced a new and original Design for a Holder for Umbrellas, Canes, or the Like, of which the following is a description, reference being had to the accompanying drawing, which forms part of this specification, and which is a view in perspective of a holder of the character described embodying my new design.

As shown in said drawing, the leading and material feature of my design consists in a holder provided with a series of helices *a*, formed and arranged to represent a serpent poised in an attitude of defiance. The lower

coil or helix of the body *a* rests upon and is secured to the supporting-base *b*. As shown, the coils increase gradually and slightly in diameter toward the top or head portion of the body, so as to form a receptacle within the coils having the shape of the frustum of a cone.

Having thus described my invention, what I claim as new, and desire to secure by Letters Patent, is—

The design for a holder for umbrellas, canes and the like, substantially as herein shown and described.

J. P. McHUGH.
